UNITED STATES PATENT OFFICE

2,563,407

ROCKER TOY

Philip L. Haims, Cleveland, Ohio

Application April 15, 1946, Serial No. 662,372

3 Claims. (Cl. 155—69)

1

My present invention pertains to the art of rocker toys for children, and a special object of the invention has been to devise such a toy or toys, in modified construction, which are made with the utmost simplicity from the viewpoint of manufacture, and which may correspondingly be sold for less than the conventional type of rocker or rocking horse toys at present commonly available at the usual sources of such toys.

Still another object of my invention has been to produce a toy of the type referred to, which is preferably made up of sheet metal for the rocker member or body of the toy, with associated handle means that may be in the form of bent tubing or bar construction, united to the sheet metal rocker body, or said body may be extended in such a manner as to provide a handle member as a part thereof.

Still another object of my invention has been to devise a toy of the above mentioned nature, equipped with stabilizing base members to prevent over-rocking movement of the rocker body or member such as would be likely to cause a child to be thrown from the rocker toy in the operation of the latter under practical conditions of use.

Still another object of my invention has been to produce a rocker toy utilizing a seat construction that may be formed directly from the sheet or flat metal rocker.

The advantages of my toy construction in the several forms thereof which I hereinafter describe in detail, will be fully comprehended upon reference to the following specification of various constructions, in conjunction with the annexed drawings, in which:

Figure 1 is a view of one form of the invention.

Figure 2 is a side elevation of the toy shown in Figure 1.

Figure 3 is a perspective view of a toy somewhat similar in form to the construction of Figures 1 and 2 with the handle means an integral part of the rocker body or member, and said body member formed with an extension providing a seat.

In the construction of my invention shown in Figures 1 and 2, there is provided here a simple curved rocker member 8, the same equipped with a suitable handle unit 9 at its front end, as generally previously described, and the rocker member 8 having a base stabilizing and actuating spring plate 10 applied to its underside at the middle portion thereof. This plate 10 is a single relatively wide plate, not quite as wide as the rocker member 8 itself, but sufficiently wide to provide stability. The plate 10 is secured to the

2

rocker member 8 by fastenings or by weld portions shown at 11.

In Figure 3 I have shown a seat type rocker toy in which the rocker member or body 12 is curved upwardly and rearwardly to provide the handle unit 13, and the handle means is supplied by slotting the unit 13 as shown at 14 to provide a gripping bar 15. The rear end portion of the rocker member 12 is also curved upwardly and bent forwardly as shown at 16 in order to provide a seat. The forwardly extending portion 16 is bent downwardly to provide a supporting member 17 for said seat, and is attached by welding or other means at the lower end flange 18 to the upper surface of the rocker member 12 intermediate the front and rear ends thereof. In this construction of Figure 3 I also utilize stabilizing plate means shown at 19 comprising two plates of resilient form welded or otherwise attached underneath the body or rocker member 12 of the toy. The rocker member 12 is therefore supported upon the plates 19 during the rocking back and forth of the toy.

From the foregoing it will be observed that I have supplied two forms of my invention, which are very simple constructions of rocker toys that can be produced very cheaply from the viewpoint of manufacture, and may be sold at very reasonable prices to meet the requirements of purchasers desiring efficient but low cost rocker toys.

It will be apparent that an important feature of the rocking toy constructions of my invention is that they are designed to enable the child to enter the rocking toy from the level of the surface upon which the toy rests. This renders the toys safe for use by small children since there is less likelihood of the child injuring himself by the necessity of climbing into the toy in a manner to overbalance the same.

Having thus described my invention, what I claim as new and desire to secure by Letters Patent of the United States, is:

1. A rocker toy of the class described, comprising a rocker base member consisting of a transversely broad curved rocker plate the bottom of which forms a broad supporting rocker surface, and a handle unit applied to the front portion of said plate and extending upwardly therefrom, said unit comprising a member extending forwardly, upwardly, and rearwardly from the front extremity of the base member, combined with a normally resilient stabilizing plate member attached to the rocker member at its bottom portion, said stabilizing plate member being normally straight and adapted to rest upon

the surface supporting the rocker toy and attached to the bottom of the curved portion of the rocker plate so as to lie directly on the supporting surface.

2. A rocker toy of the class described, comprising a rocker base member consisting of a transversely broad curved rocker plate the bottom of which forms a broad supporting rocker surface, and a handle unit applied to the front portion of said plate and extending upwardly therefrom, said unit comprising a member extending forwardly, upwardly, and rearwardly from the front extremity of the base member, combined with a stabilizing plate of resilient metal attached to the under side of the rocker member and projecting rearwardly from the upwardly curving rear portion of the latter, said stabilizing plate being flat and straight.

3. A rocking toy comprising a curved rocking member, the front and rear ends of which curve upwardly and the rear end of which is bent forwardly and downwardly to provide a seat, the front curved portion of the rocking member be-

ing equipped with handle means, said handle means being formed by bending the front end portion of the rocker member rearwardly and providing a slot to make a handle bar adjacent the seat.

PHILIP L. HAIMS.
